Raymond Jacob Leach
by Chas. H. Luther

ATTORNEY.

UNITED STATES PATENT OFFICE.

RAYMOND JACOB LEACH, OF SEEKONK, MASSACHUSETTS.

SIGHT-FEED OIL-CUP.

1,044,062.

Specification of Letters Patent. Patented Nov. 12, 1912.

Application filed June 19, 1912. Serial No. 704,658.

To all whom it may concern:

Be it known that I, RAYMOND JACOB LEACH, a citizen of the United States, residing at Seekonk, in the county of Bristol and State of Massachusetts, have invented a new and useful Improvement in Sight-Feed Oil-Cups, of which the following is a specification.

My invention has reference to an improvement in oil cups and more particularly to an improvement in sight feed oil cups for two-cycle gas engines.

In the usual construction of sight feed oil cups and when used on two-cycle gas engines, the oil feeds by gravity and the gas pressure in the engine casing works back through the oil duct into the oil cup and prevents the proper feeding of the oil from the cup, by virtue of the back pressure of the gas being greater than the weight of the oil, and this back pressure varies in different makes and sizes of engines.

The object of my invention is to improve the construction of a sight feed oil cup for two-cycle gas engines, whereby back pressure of the gases from the engine casing into the oil cup is eliminated, and I accomplish this object by providing the oil cup with an automatic ball check valve either above or below the sight feed, said valve having means for adjusting the same for varying pressures in different makes or sizes of engines.

A further object of my invention is to construct a sight feed oil cup for two-cycle gas engines with a ball check valve so constructed that the valve controls the oil feed and also prevents the gas pressure in the engine casing from entering the oil cup.

My invention consists in the peculiar and novel construction of a sight feed oil cup for two-cycle gas engines, said oil cup having details of construction as will be more fully set forth hereinafter and claimed.

Figure 1 is a vertical front view of my improved oil cup showing the combined oil feed valve, back pressure valve and sight feed tube above the sight feed glass. Fig. 2 is a vertical sectional view taken on line 2-2 of Fig. 1. Fig. 3 is an upper end view of the cylindrical valve member. Fig. 4 is a side view of the cylindrical valve member, and Fig. 5 is a vertical sectional view similar to Fig. 2 of a modified form of oil cup, showing the back pressure valve below the sight feed.

In the drawings 7 indicates the top, 8 the glass cylinder and 9 the base forming the oil cup proper. The base 9 has the usual central tube 10 to which the cover 7 is secured. The tube 10 has a vertical oil duct 11, and transverse oil ducts 12, 12, forming outlet ducts from the cup into the tube, at the bottom of the cup. The base 9 has a downward extension 13 externally screw-threaded at the end 14, a vertical cylindrical valve chamber 15, a valve seat 16 at the intersection of the upper end of the valve chamber 15 and the lower end of the oil duct 11, a transverse screw-threaded hole 17 and a stop pin 18 extending into the valve chamber at the bottom. A cylindrical valve member 19 is constructed to have a sliding fit in the chamber 15, a circular recess 20 and a transverse oil slot 21 in its upper end, a central vertical oil duct 22, terminating downward into an oil drip tube 23, and a round hole 24 in the side, as shown in Figs. 2, 3, and 4. A ball valve 25 is centrally supported by the upper end of the valve member 19 in a position to engage with the valve seat 16, the top pin 18 limiting the downward movement of the valve member. A thumb screw 26 having a cone shaped end 27 is screwed through the hole 17 in a position for the cone shaped end 27 to engage with the upper edge of the hole 24 in the valve member 19 as shown in Fig. 2. The sight feed member 28 has an internally screw-threaded upper end 29 secured to the end 14 of the extension 13, a cylindrical chamber 30 with side openings 31, 31, the usual sight feed glass cylinder 32, nut shaped portion 33 screw-threaded lower end 34 and vertical oil duct 35 which extends from the chamber 30 through the screw-threaded end 34, as shown in Fig. 1.

In the modified form as shown in Fig. 5 the base 9 has the usual drip tube 36 and valve seat 37, formed in the base, and a rod valve 38 operated from the cover, by the usual means not shown, controls the flow of oil from the cup. In this form the back pressure valve mechanism is placed below the sight feed glass 32 and its operation is independent of the oil feed. When in use the ball valve 25 is held centrally over the oil duct 22, and centrally under the valve seat 16, whereby back pressure of the gases through the duct will act to instantly close the valve and positively prevent the entrance of a gas or back pressure into the oil

cup. The valve is adjusted or closed by turning the thumb screw 26, the cone shaped end 27, acting on the upper edge of the hole 24 in the valve member 19, to raise or 5 lower the valve member 19, and the ball valve 25.

Having thus described my invention I claim as new and desire to secure by Letters Patent:—

- 10 1. In a sight feed oil cup, an oil duct leading from the cup, a valve chamber below the oil duct, a valve seat at the intersection of the oil duct and the valve chamber, a slide-
15 able valve member in the valve chamber, an oil duct extending through the valve member, a ball valve supported centrally under the valve seat directly by the valve member, and auxiliary means co-acting with the valve member for adjusting the valve member to adjust the ball valve relative to the valve seat.
- 20 2. In a sight feed oil cup, an oil duct leading from the cup, a valve chamber below the oil duct, a valve seat at the intersection of the oil duct and the valve chamber, a slide-
25 able valve member in the valve chamber, a drip tube on the lower end of the valve member, an oil duct extending through the valve member and drip tube, a ball valve supported centrally under the valve seat by the valve member, and means for adjusting the valve member to adjust the ball valve relative to the valve seat.
- 30 3. In a sight feed oil cup, an oil duct leading from the cup, a downward extension on the cup, a valve chamber in the downward extension, a valve seat at the intersection of the oil duct and the valve cham-
- 35

ber, a slideable valve member in the valve chamber, a drip tube on the lower end of the valve member, an oil duct extending through the valve member and the drip tube, said valve member having a recess in its upper end and a hole in its side, means adapted to engage with the hole in the side 45 of the valve member to adjust the valve member, whereby the ball valve is adjusted relatively to the valve seat.

4. In a sight feed oil cup, an oil duct leading downward from the cup proper, a 50 downward extension on the cup, a valve chamber in the downward extension, a valve seat at the intersection of the oil duct and the valve chamber, a slideable valve member in the valve chamber, a drip tube on the 55 lower end of the valve member, said valve member having a hole in its side, a recess in its upper end, transverse oil slots extending through the recess and a central longitudinal oil duct extending from the 60 recess through the drip tube, a thumb-screw having a cone shaped end and screw-threaded through the wall of the downward extension in a position for the cone shaped end to engage with the upper edge of the 65 hole in the side of the valve member and means for limiting the outward or downward movement of the valve member.

In testimony whereof, I have signed my name to this specification in the presence of 70 two subscribing witnesses.

RAYMOND JACOB LEACH.
